INSULATION CUTTING TOOL

James N. Rollings, Baltimore, Md., assignor to
Western Electric Company, Incorporated, New
York, N. Y., a corporation of New York

Application March 27, 1943, Serial No. 480,878

2 Claims.

(Cl. 81—9.5)

This invention relates to insulation cutting tools and more particularly to tools for stripping predetermined lengths of insulation from cable cores.

In preparing a multiconductor cable to be attached to the terminals of a connecting plug, or other electrical device, the insulating jacket surrounding the group of conductors forming the core is removed for a predetermined distance from the end of the cable and then portions of the insulation on the individual insulated conductors are removed from the ends of the conductors for a predetermined distance to bare the desired amount of the conductors. The insulation employed in such cables may be a tough, elastic, vulcanized rubber composition or other tough plastic materials.

In removing the insulation from the individual conductors, the lengths of the insulation removed therefrom should be uniform. Previously the amount of insulation removed depended upon the judgment of the operator and thus was subject to errors. If the length to be stripped were measured in each case, this operation required too much attention and time of the operator.

It is an object of this invention to provide new and improved insulation cutting tools.

The particular embodiment of the invention described herein comprises a tool resembling pliers provided with a pair of crossed pivoted members having cutting blades removably attached, each of which blades has an arcuate cutting edge, straight cutting edges and abutments formed thereon, and a gauge adjustably attached to one of the crossed member to permit an insulated conductor to be inserted between the cutting blades only a predetermined distance from the gauge.

The invention may be fully understood from the following description, taken in conjunction with the accompanying drawing, in which

Fig. 1 is a perspective view of a cutting tool embodying the invention;

Fig. 2 is a fragmentary side elevation thereof;

Fig. 3 is a fragmentary sectional view thereof taken along the line 3—3 in Fig. 2, and

Fig. 4 is a plan view of a portion of the tool.

Referring to Fig. 3 of the drawing, a jaw 10 having a semicylindrical groove 11 therein is formed on one end of a lever 12 having a handle 13 at the opposite end thereof. A cutting blade 14, removably secured by screws 16—16 in a socket 15 formed in the top end of the jaw 10, has abutments 17—17 (Fig. 4) projecting slightly beyond straight cutting edges 18—18 and an

arcuate cutting edge 19 formed thereon. An L-shaped gauge 20 is adjustably secured to the jaw 10 by screws 22—22 extending through an elongated slot 21 formed therein. The gauge 20 has an arcuate surface 23 formed at one side of a transverse arm 24 thereon to permit an individually insulated conductor 25 to pass between the jaw 10 and a companion jaw 26 formed at one end of a lever 27 having a handle 28 at the opposite end thereof.

The jaw 26 projects transversely from the lever 27 and has a semicylindrical groove 29 therein opposite the groove 11 in the jaw 10. A cutting blade 30, removably secured by screws 31—31 in a socket 32 formed in the jaw 26, has formed thereon abutments 35—35 projecting slightly beyond straight cutting edges 33—33 and an arcuate cutting edge 34 similar to those on the blade 14. The levers 12 and 27 are pivotally connected by a pin 36, so that when the handles 13 and 28 are moved inwardly the abutments 17 and 35 are brought into contact with each other and prevent the cutting edges 18—18 and 33—33 from contacting each other. However, the clearance between these cutting edges is very slight and is insufficient to prevent them from cutting and stripping insulation satisfactorily.

To prepare the end of a cable 38 (Fig. 1) for connection to a cable plug or other electrical device, an outer insulating jacket 37, composed of a vulcanized rubber composition or the like, is severed to form a shoulder 39, and the severed portion of the jacket 37 is removed from the individually insulated conductors 25 and 40. The individual conductors 25 and 40 comprise insulating coverings 42 and 43 made of a vulcanized rubber compound, or similar material, surrounding conducting cores, such as the stranded conductor 44. In order to affix a connecting plug to the end of a cable of this construction, it is desirable to have the insulation stripped from the individual conductors for a given distance from the ends of the conductors and also to have predetermined lengths of the insulated conductors between the stripped portions of the conductors and the shoulder 39 formed on the outer jacket 37 when the jacket is stripped from the free ends of the insulated conductors. The appearance of the finished ends of the stripped conductors is illustrated by the conductor 40 (Fig. 1).

To make the conductor 25 correspond to the stripped conductor 40, the gauge 20 is first adjusted to the position desired and secured by the screws 22—22. The cable 38 is then positioned

with the shoulder 39 of the outer jacket 37 bearing against the outer side of the arm 24 of the gauge 20 and with the conductor 25 resting against the arcuate surface 23 on the arm 24 and upon the blade 14 above the groove 11. The handles 13 and 28 are drawn together to force together the jaws 10 and 26 and the abutments 17-17 and 35-35 on the blades 14 and 30, respectively, thereby causing the straight cutting edges 18-18 and 33-33 and the arcuate cutting edges 19 and 34 to cut through the insulation 42 to the conductor therebeneath. The cutting tool is then rotated about the conductor 25 to completely sever the insulation, whereupon the severed portion of the insulation may be stripped from the conductor 25 by drawing the tool away from the free end of the conductor. The cutting edges 18-18 and 33-33 are prevented from contacting and thus injuring each other, by the projecting abutments 17-17 and 35-35, although the clearance between the cutting edges is so slight as to be almost unnoticeable.

This operation is facilitated by the gripping action of the grooves 11 and 29 upon the severed portion of the insulation 42 which protrudes therebetween. Since the arcuate cutting edges 19 and 34 coact to form a substantially circular opening, the diameter of which is just about the same as that of the conductor, the conductor is not injured when the insulation is severed.

Obviously, with the gauge 20 set in a given position, all lengths of the bared conductors will be uniform. If different lengths of the conductors are desired to be bared, the screws 22-22 may be loosened and the gauge 20 may be adjusted lengthwise with respect to the jaw 10 and secured in the adjusted position by re-tightening the screws 22-22.

If the blades 14 and 30 become dull or damaged, they may be removed readily for sharpening or replacement by removing the screws 16-16

and 31-31. When it is desired to strip the insulation from a conductor of a different diameter, the blades 14 and 30 may be removed and replaced with blades having arcuate cutting edges 19 and 34 conforming to the diameter of this conductor.

It will be understood that modifications may be made in the herein described embodiment of the invention without departing from the spirit and scope of the invention, which are limited only by the appended claims.

What is claimed is:

1. A wire stripping tool comprising a pair of jaws having complementary semicylindrical grooves therein, a pair of stripping blades removably secured to the jaws and having arcuate cutting edges thereon, and a gauge having a transverse arm provided with an arcuate cut out portion positioned outwardly from the blades, which gauge is adjustably secured to one of the jaws so that the arm projects a predetermined distance beyond the cutting blades for severing a predetermined length of insulation from a conductor inserted between the jaws and against the gauge.

2. A wire stripping tool comprising a pair of jaws having complementary semicylindrical grooves therein, a pair of stripping blades removably secured to the jaws and having contiguous, arcuate and straight cutting edges thereon and abutments thereon to prevent the straight cutting edges from striking each other, and a gauge having a transverse arm provided with an arcuate cut out portion positioned outwardly from the blades, which gauge is adjustably secured to one of the jaws so that the arm projects a predetermined distance beyond the cutting blades for severing a predetermined length of insulation from a conductor inserted between the jaws and against the gauge.

JAMES N. ROLLINGS.
